ANTITHEFT STEERING WHEEL LOCKING APPARATUS

Lawrence I. Holtzworth, 28739 Kenroy Ave., Saugus, Calif. 91350, and Zoltan J. Varga, 5450 Russell Ave., Hollywood, Calif. 90027

Filed July 6, 1971, Ser. No. 160,240

Term of patent 14 years

Int. Cl. D8—07
U.S. Cl. D8—113

FIG. 1

FIG. 2

FIG. 3

FIG. 4

FIG. 5

FIG. 1 is a side elevational view of an example of a first species of an antitheft steering wheel locking apparatus embodying the claimed design.

FIG. 2 is a plan view thereof.

FIG. 3 is a side elevation view of the right hand portion of a second species thereof, the left hand element being omitted for convenience of illustration.

FIG. 4 is a plan view of the left hand, generic element shown withdrawn from its telescoping disposition within the right hand portion thereof said element being common to both forms claimed.

FIG. 5 is a side elevational view of the element thereof shown in FIG. 4.

We claim:

The ornamental design for an antitheft steering wheel locking apparatus, substantially as shown and described.
